ABSTRACT OF THE DISCLOSURE

The disclosure describes a particle removing and transfer system mounted in the center of a rectangular storage facility for removing particles from a particle pile and transferring the particles to apertures formed in the storage floor. The storage floor has inclined surfaces that extend downward from the center to the walls. The transfer system includes a plurality of drag lines or drag means each having one end thereof attached to a continuous chain that follows an elongated path about a diagonal axis. The drag lines have digging elements mounted thereon for moving against the base of the pile to remove particles therefrom.

BACKGROUND OF THE INVENTION

This invention relates to particle storage facilities and more particularly to particle storage facilities that are noncircular in cross sectional and that have transfer systems mounted in the center of the facility for systematically removing particles from a particle pile.

Many particle materials such as silage, sawdust, and vermiculite are stored in enclosures in which the particles are irregularly dumped through the top of the enclosure to form a particle pile within the enclosure. Frequently, it is necessary to remove the particles from the enclosure in a systematic and continuous flow. This is particularly important in the case of sawdust that is utilized as a source of fuel for power generation plants such as those commonly found in lumber, paper and plywood mills. Generally a conveyor system is mounted below the floor of the enclosure or storage facility for receiving the sawdust that falls by gravity through the apertures of the floor. However, over a period of time sawdust has a tendency to form arcs or to "bridge" over the apertures in the floor, thereby stopping the flow of sawdust.

To manually break the bridge is costly and dangerous. Several persons have lost their lives attempting to break the bridges that had formed in enclosures. Prior efforts to overcome the difficulty has been largely directed towards the use of rigid mechanical digging devices that are either rotated or extend radially outward from the center of cylindrical storage facilities as shown in U.S. Patents 2,755,942 and 2,736,461 or which extend diametrically across the pile as shown in U.S. Patents 2,792-153 and 2,496,146. In my U.S. Patent No. 3,011,658, I disclose an apparatus for transferring sawdust from the base of the pile. The apparatus includes a circular ring circumscribing the base of the pile that is powered to turn about the center of the support floor. One end of a drag line is connected to the ring and the free end extends inwardly. As the ring rotates the angular movement of the ring causes the free end of the drag line to be urged inwardly against the base of the sawdust pile to remove sawdust from the pile and to break bridges that form in the sawdust pile.

In my copending application Ser. No. 666,614 I provide a particle transferring means for use in non-cylindrical storage facilities. The apparatus includes a substantially rectangular track that circumscribes a particle

2

pile. A continuous chain is mounted in the track for pulling one end of a drag line about the inside of the enclosure. The floor of the enclosure has inclined surfaces that extend downward from the side walls of the enclosure towards the center to bias the free end of the drag line toward the center of the facility.

One of the principal objects of this invention is to provide a central particle transfer means for efficiently, economically and reliably removing particles from the base of a particle pile located in a noncylindrical enclosure.

An additional object of this invention is to provide an apparatus for removing particles from the base of the pile in which the particle removal apparatus is located substantially in the center of the enclosure.

A further object of this invention is to provide a central particle removing apparatus for a noncylindrical storage facility that is efficient in removing particles from the pile and is capable of operating even through large forces are exerted on digging elements of the apparatus.

These and other objects will become apparent upon reading the following detailed description of a preferred embodiment of this invention.

BRIEF DESCRIPTION OF THE DRAWINGS

A preferred embodiment of this invention is illustrated in the accompanying drawings, in which:

FIG. 1 is an elevated prespective view of a storage facility that has a noncircular horizontal cross section;

FIG. 2 is a plan view of the particle storage facility showing a particle transfer means mounted in the center of the facility for moving the drag lines over a storage facility floor that has inclined surfaces that extend from the center of the facility downward to the side walls of the facility;

FIG. 3 is a vertical cross sectional view taken along line 3—3 in FIG. 2;

FIG. 4 is a cross sectional view taken along line 4—4 in FIG. 2;

FIG. 5 is a fragmentary side view showing a section of a drive means for moving the drag lines over the floor; and

FIG. 6 is a fragmentary plan view of a section of one of the drag lines showing digging elements for removing particles from the base of the pile.

DETAILED DESCRIPTION OF THE PREFERRED EMBODIMENT

Referring in detail to FIG. 1, there is shown a particle storage facility which is generally designated by the arrow 10. The facility has a rectangular horizontal cross section with end walls 11 and 12 and side walls 13 and 14 surrounding a floor 20 that supports the particles. The intersection of the floor with the end walls and side walls forms corners 15, 16, 17 and 18 respectively (FIG. 2). The floor 20 has inclined flat surfaces 21 and 22 that slope from a center ridge 23 outwardly toward the side walls and the corners 16 and 18 with the slope of the inclined surfaces 21 and 22 being at an acute horizontal angle with the side wall. The center ridge 23 extends along a horizontal diagonal axis L of the storage facility. The diagonal axis L is at an acute horizontal angle with respect to the end walls 11 and 12.

The slope of the inclined surfaces 21 and 22 is less than the angle of repose of the particle material. For the purpose of illustration only, the slope of the surfaces 21 and 22 is shown at approximately 30°. With this slope the particles will conform to the sloping floor when dumped into the facility.

Elongated cross apertures 25 and 26 are formed in the inclined surfaces 21 and 22 respectively for permitting

the flow of the particles therethrough. Elongated end apertures 26 and 27 are formed in the floor along the center ridge 23 adjacent the end walls respectively for permitting the flow of particles therethrough. Grating 30 is mounted in the apertures 25-28 for permitting the flow of particles therethrough while providing support for particle removing equipment that moves over the apertures.

A conveying system is mounted below the floor for receiving the particles and conveying the particles from the storage facility 10. The conveying system includes two cross conveyors 32 and 33 mounted immediately below these apertures 25 and 26 respectively. Cross conveyors 32 and 33 convey the particles upwardly and inwardly toward the center to a main conveyor 34 that extends the full length of the storage facility and immediately below the apertures 27 and 28 for conveying the particles from the storage facility.

In cooperation with the inclined surfaces 21 and 22, the storage facility has a particle transfer system that removes the particles from the base of a particle pile supported on the floor and moves the particles to the apertures 25-28. The particle transfer system includes four or more drag means 36 that are pulled over the floor by an elongated drive means 37. The drive means 37 is mounted in the center of the facility along the center ridge 23. An elongated shield 38 is mounted immediately above the drive means 37 to support a portion of the particle pile and to prevent the particles from clogging the drive means.

The drive means 37 includes a double link continuous chain 40 (FIG. 5) that is mounted between a horizontal drive sprocket 41 and a horizontal idler sprocket 42 to form an elongated continuous path along the diagonal axis L. The horizontal drive sprocket 41 is mounted on a vertical drive shaft 43 that extends upwardly through the floor 20. The shaft 43 is rotatably supported by an upper bearing 44 and a lower bearing 45. The bearings 44 and 45 are mounted on brackets 46 and 47 respectively as shown in the fragmentary view FIG. 5. The shaft 43 is rotated by a conventional power drive with a pulley 48 mounted to the lower end of the shaft.

The horizontal drive sprocket 41 has two spaced sprocket wheels 49 and 50 for engaging the space double links of the chain. Each link of the chain is separated by cylindrical spacers 52.

The drag means 36 includes four or more flexible cables 54, 55, 56 and 57 that are pivotally attached to the chain 40 at spaced intervals. The flexible cable 54 is attached to the chain at point 61. The flexible cable 55 is attached to the chain at point 62. The flexible cable 56 is attached to the chain at point 63 and the flexible cable 57 is attached to the chain at point 64. A fitting 58 (FIG. 5) is affixed to one end of each flexible cable. The fitting 58 is affixed to a collar 59 that is rotatably mounted about one of the spacers 52 of the chain.

Digging elements 66 are mounted on each cable adjacent to its free end for engaging the base of the particle pile and removing particles therefrom. Each of the digging elements 66 includes a socket 67 (FIG. 6) affixed to the cable. A sleeve 68 is coaxially mounted about the cable with one end affixed to the socket 67. An annular abutment 70 is formed about the outer circumference of the sleeve 68. A digging disc 69 is coaxially mounted about the sleeve 68 with a hub 72 of the disc engaging the annular abutment 70 to prevent the axial movement of the hub along the sleeve 68. A weighted hook 73 is fixed to the free end of each cable to urge the free end down the inclined surfaces 21 and 22. Each of the hooks 73 are wheel supported to facilitate the movement of the hook down the inclined surfaces toward the walls.

Each of the flexible cables 54-57 is of a sufficient length so that the cable will extend around at least one end of the elongated path of the continuous chain 70

to prevent lateral force being applied to the chain from the cable. For example, as shown in FIG. 2 cable 54 is attached to the chain at point 61. The chain then extends rearward along the side of the chain 40 and then around the idler sprocket 42. The flexible cable 55 is attached to the chain at point 62 and extends around the drive sprocket 41 and then along the side of the chain and then around the idler sprocket 42. From this description it can be appreciated that the pulling force of the cable is directed tangentially to the chain at the point of connection and that each cable extends at least one of the sprockets to provide additional frictional engagement to sustain high pulling forces.

To assist the digging elements to move around each end of the elongated drive means, an annular guide 76 (FIG. 5) is fixed to each of the sprocket shafts. Each of the guides 76 has a conical surface 77 that provides a movable surface for supporting the digging elements and carrying the digging elements around each end of the elongated drive means.

During the operation of the facility the particles fed into the particle storage facility and descending to the floor to form a pile conforming to the shape of the enclosure. The angle of the inclined surface 21 and 22 is less than the angle of repose of the particles but is sufficient to bias the free ends of the drag means outwardly toward the walls of the facility. The angle of the inclined surfaces 20 and 21 is sufficient to permit the free end of the flexible drag means to slide or roll toward the side and end walls to bias the discs 69 against the base of the pile. As the drag means 36 move over the floor the particles are removed from the base of the pile and pulled over the aperture 25-28. The drag means work from the inside out to gradually eat into the base of the pile in a systematic manner for preventing the formation of bridges over the floor apertures and to provide a constant flow of particles onto the conveyor system.

It should be understood that the above described embodiment is simply illustrative of the principles of this invention and numerous other modifications may be made without deviating from the principles thereof. Therefore, only the following claims are intended to define my invention.

What I claim is:

1. A particle storage facility for receiving particles such as sawdust in a pile and for removing the particles from the base of the pile, said facility having side walls in combination with the improvement of:
  - (a) a floor for supporting the pile, said floor having inclined surfaces that extend outwardly and downwardly from the center to the side walls at a slope less than the natural angle of repose of the particles to prevent the natural flow of the particles toward the side wall, said floor having at least one aperture formed therethrough for permitting the flow of particles therethrough;
  - (b) a particle conveying means below the floor aperture for receiving the particles and conveying the particles from the storage facility;
  - (c) elongated drag means slidably mounted on the floor for engaging the base of the pile; and
  - (d) a drive means positioned in the highest portion of the floor and connected to one end of the drag means for moving the drag means over the floor with the free end of the drag means biased down the inclined surfaces by gravity against the base of the pile to remove the particles from the pile and move the particles to the floor aperture and onto the conveyor means for conveyance from the storage facility.
2. A particle storage facility as defined in claim 1 wherein the drive means includes a continuous drive chain that follows an elongated path with spaced ends and

wherein each drag means is flexible with one end pivotally connected to a segment of the chain.

3. A particle storage facility as defined in claim 2 wherein each drag means includes a flexible cable that is of sufficient length to extend about at least one end of the path of the drive chain.

4. A particle storage facility as defined in claim 1 wherein the storage facility is substantially rectangular in cross section with end walls and side walls in which the distance between the side walls is less than the distance between the end walls and wherein the slope in the inclined floor surfaces is at an acute angle to the side walls and wherein further the drive means is elongated and aligned along a horizontal diagonal line that is at an acute angle to the end walls.

5. A particle storage facility as defined in claim 4 wherein the elongated drive means includes a continuous chain that follows an elongated path about spaced chain sprockets defining two spaced ends of the elongated path.

6. A particle storage facility as defined in claim 5 wherein each drag means includes a flexible cable connected to a segment of the chain in which the cable is

of sufficient length to extend around at least one end of the elongated path at all times to prevent lateral force being applied to the chain.

7. A particle storage facility as defined in claim 6 wherein each drag means further includes digging elements mounted on the cable adjacent the free end for engaging the base of the particle pile and wherein the drive means further includes rotating guides positioned at the ends of the elongated path for assisting the movement of the digging elements of the drag means around the ends of the elongated path.
